UNITED STATES PATENT OFFICE.

JAMES H. BAKER, OF ALLEGHENY, PENNSYLVANIA.

DESIGN FOR A BRAKE-ROD END.

SPECIFICATION forming part of Design No. 35,622, dated January 28, 1902.

Application filed December 3, 1901. Serial No. 84,587. Term of patent 7 years.

To all whom it may concern:

Be it known that I, JAMES H. BAKER, a citizen of the United States, residing at Allegheny, in the county of Allegheny and State of Pennsylvania, have invented and produced 5 a certain new and original Design for Brake-Rod Ends, of which the following is a specification.

In the accompanying drawings, forming part 10 of this specification, Figure 1 is a side elevation of the coupling-jaws for brake-rods or brake-rod ends, showing my new design; and Fig. 2 is an edge elevation of the same.

As shown in the drawings, the leading features of my design consist of a substantially 15 round stem 1, from which arms 2 extend, said arms being substantially square in cross-section. The arms are substantially parallel with the axis of the stem 1 and with each 20 other, except the inner portions 2^a thereof,

said portions forming substantially equal angles with the stem 1 and the main portions of the arms. At their outer ends the arms have circular enlargements or disks 3, having central openings 4 therein. Concave bevels 5 25 extend in both directions from a rib 6 around the outer edges of the disks to the junctions of the disks with the arms.

Having described my invention, what I claim as new, and desire to secure by Letters 30 Patent, is—

The design for a brake-rod end as herein shown and described.

In testimony whereof I have hereunto set my hand.

JAMES H. BAKER.
